CLAIM

The ornamental design for a poop bag dispenser, as shown and described.

DESCRIPTION

FIG. 1 is a perspective view of a poop bag dispenser showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a bottom plan view thereof; and,

FIG. 8 is a top plan view thereof.

The dashed or broken lines shown in the drawings depict portions of the poop bag dispenser in which the design is embodied that form no part of the claimed design.
